COMBINED MANUAL AND AUTOMATIC ROUTE CONTROL SYSTEM FOR RAILROADS

Frank T. Pascoe, Scott Township, Allegheny County, Pa., assignor to Westinghouse Air Brake Company, Wilmerding, Pa., a corporation of Pennsylvania

Application July 27, 1951, Serial No. 238,799

15 Claims. (Cl. 246—2)

My invention relates to a combined manual and automatic route control system for railroads by means of which, at the will of an operator, certain traffic routes over the track switches of a manually controllable interlocking plant may be set up and the corresponding entering signals cleared automatically in accordance with the 20 destinations of approaching trains.

More particularly, my invention relates to the automatic control of the switches and signals of an interlocking plant by a train describer system of the type adapted to automatically and successively display at a wayside station indications of the route, class or destination of each of a series of trains which approach the station over the same stretch of railway track, and in which the indication of each train is cancelled upon its arrival at the station and then superseded by the indication for the next following train.

My invention is particularly adapted for use in connection with a train describer system of the type in which the route indications are both supplied and cancelled automatically by the action of route identifying marker devices on the approaching trains without dependence upon track circuits for indicating the arrival or departure of such trains.

The primary object of my invention is to provide the maximum protection against improper operation of the track switches and signals under conditions involving their automatic operation as the result of train movements.

A specific object of my invention is to provide improved manual change-over or transfer means for placing the switches and signals alternatively under manual control, or under automatic control by a train describer system. This change-over means functions in such a manner as to insure that a shift to automatic control will be made only when no train is approaching within a predetermined distance of the automatically controllable routes or is occupying one of these routes or a conflicting route.

A feature of my invention resides in the control of this change-over means so that the system automatically terminates the automatic control upon the approach of a train which is not identified by the train describer system, with the object of insuring that a route will not be set up for an unidentified train as the result, for example, of the storage in the train describer system of a route indication for a following train.

A further object of my invention is the provision of additional protection under automatic operation against the release of the usual switch locking during the passage of a train over a route due to poor shunting of a track relay or the like. Conventionally, under manual operation, a circuit for rendering the switch locking ineffective is prepared by energizing an approach locking stick relay by the release of a track relay when a train enters a route and the circuit is completed by the energization of the same or of another track relay when the route is vacated. In accordance with a feature of

2

my invention the approach locking relay does not become energized when a train enters the route but remains released to maintain the switch locking effective until the end of a predetermined time interval which does not begin until the train has vacated the route.

This feature of my invention is applied to the locking for each route which conflicts with an automatically controllable route.

In the following one form of apparatus embodying my invention will be described and the novel features thereof will then be pointed out in claims.

In the accompanying drawings, Fig. 1A shows a diagram of a stretch of railway track equipped with an interlocking control system arranged for automatic control by a train describer system, in accordance with my invention, together with the circuits and apparatus of the train describer system by means of which approaching trains automatically indicate their route, class or destination by the selective lighting of one of the lamps in a display indicator shown at the lower right in this view. Fig. 1B shows circuits for the route selecting relays of an interlocking control system of the route type controllable by push buttons which designate the opposite ends of the different routes, with the circuits modified to include the change-over means of my invention together with relays governed thereby which enable the train describer system to automatically operate the selecting relays for certain routes. Fig. 1C shows a diagram of that portion of the track plan of Fig. 1A which includes the interlocked traffic routes, together with circuits and apparatus governed by the route selecting relays and by locking relays in accordance with signal and track conditions, for operating the interlocked track switches and for indicating their position. Fig. 1D shows circuits for route relays controlled by the route selecting and switch indication relays for governing the clearing of the signals. Fig. 1E shows circuits for the mechanisms for the entering signals for the interlocked traffic routes, together with a diagram of the same portion of the track plan as is shown in Fig. 1C. Finally, Fig. 1F shows circuits for approach and time locking relays controlled by the route relays and by the signals, by means of which the track switches and opposing signals are electrically interlocked.

Similar reference characters refer to similar parts in each of the several views, and to simplify the circuit diagrams, only the terminals of the local sources of current for energizing the various relays are shown, these being identified by the reference characters B and N, respectively.

Referring to Fig. 1A, it is to be understood that the track plan shown is a portion of a railroad employing electric traction. In the plan, the rails are represented diagrammatically by a single line, and it is to be understood that the rails are divided by insulated joints to form the series of track sections 1T, 2T, 10T, 12T, 14T and 16T, each of which is equipped with a normally closed alternating current track circuit having a correspondingly numbered track relay TR supplied with energy over the rails of its section from a suitable source of alternating current designated BX.

To simplify the drawings, only the minimum amount of apparatus deemed necessary to illustrate the principles of my invention is shown, and accordingly, the interlocking plant shown is one having only a single pair of power operated track switches 1A and 1B, and the train describer system is arranged to provide only two route indications. The various routes through the plant will be designated by the numbers which identify the signals at their opposite ends, as in Fig. 1C, and they include the routes 2—6, 2—8 and 4—8 having the entering signals 2A, 2B and 4, respectively, and the opposing routes 6—2,

8—2 and 8—4 for which the entering signals are 6, 8B and 8A, respectively. Of these, only the routes 2—6 and 2—8 are controllable automatically.

The approach zone for signals 2A and 2B comprises the track sections 10T, 12T and 14T, and its occupancy by a train is indicated in the conventional manner by the release of an approach relay 2AR controlled over front contacts *a* of the track relays 10TR, 12TR and 14TR for these sections.

Relay 2AR and the track relays 1TR and 2TR control indication lamps on an illuminated track diagram, not shown herein, by means of which the positions and movements of trains are indicated in a control tower in accordance with the usual practice.

Briefly described, the apparatus of my invention includes a manual change-over switch operable between two positions for designating manual and automatic control, respectively, which is incorporated in the route selecting push button 2PB, Fig. 1B, of the interlocking control system, together with a change-over stick relay APBS which may be picked up to transfer the system from manual to automatic control by pressing the button 2PB when the change-over switch is in its automatic position, but only if the automatically controllable routes are unoccupied and the approach zone therefor is also unoccupied. The circuits incorporate the non-storage principle to insure that the transfer to automatic control will be made only under manual supervision and will not be made under my unsafe traffic conditions relative to the switch locking.

When relay APBS is energized, the route selecting relays of Fig. 1B by which routes 2—6 and 2—8 are established are controllable automatically by the repeating relays AP and BP, respectively, governed by the train describer system in accordance with the indicated route for the approaching train. When the automatic control is in effect, the manual control of non-conflicting routes is not interfered with, for example, route 4—8 or 8—4 may be set up manually, except when route 2—8 is set up.

In accordance with a feature of my invention, the change-over relay APBS is maintained energized either by the track relay 14TR for the entering section 14T of the approach zone, or by a directional stick relay 14SR controlled by relay 14TR and by the train describer system, in such a manner that relay APBS releases to disable the automatic control on the approach of any train which fails to actuate the train describer system to register an indication of its route.

This is desirable for the reason that the route for any train which does not actuate the train describer system should be set up by manual control. If this is not done, the automatic control system would be in condition to be actuated by a following train upon entering the occupied approach zone to set up a route which although established by the second train could be accepted by the first train regardless of the wishes of the operator, with the result that he would lose control of that train. It will be clear that this difficulty is avoided by the automatic release of the change-over relay APBS in the event that a transfer from automatic to manual control, under the conditions described, has not already been made manually.

In addition, relay APBS when energized opens the circuits in Fig. 1F by which otherwise an approach locking relay AS controlled by the entering signal would be re-energized automatically when a train enters an established route.

Under manual operation, although the release of the track relays for the switch sections is depended upon primarily to insure that the switches will remain locked until the route is vacated, additional protection is provided by incorporating the non-storage principle in the switch control circuits. In accordance with this principle, if the control means is operated when the switches are locked, the result is merely to hold them locked, and the

control means must be restored to its original condition and reoperated at a time when the switches of the route are not locked, in order to effect their operation. In order to provide a corresponding measure of additional protection under automatic operation, the circuits of my invention are arranged to maintain the switch locking effective after a route has been occupied, until it is certain that it has been vacated as manifested by the fact that the track relay has remained steadily energized for a predetermined time locking period during which the track relay for each section of the route is steadily energized.

Before describing the operation of the apparatus of my invention in detail, the block signaling system, the train describer system and the interlocking control system will each be briefly described, for the reason that knowledge of the general mode of operation of these systems is deemed necessary for an understanding of my invention.

Considering first, the signaling system, it is to be understood that the trains which traverse the stretch of track shown are equipped with automatic speed control and cab signaling apparatus of the well-known continuous inductive type, such as is illustrated typically in Letters Patent of the United States No. 2,235,037, granted March 18, 1941, to F. H. Nicholson et al. This apparatus is controlled by periodically interrupting or coding the alternating track circuit current supplied to the rails, at different rates, and in such a manner as to provide an overlap block system of control so that, for example, when signals 2A and 2B indicate stop, as shown, the aspects of the cab signals on an approaching train correspond to those indicated by the wayside signal symbols 10, 12, 14 and 16. That is to say, an approaching train will be governed by a green proceed signal in section 16T, by a yellow over green approach medium signal in section 14T and by a yellow approach signal in section 12T, due to the fact that the alternating current supplied to the rails of these sections is coded, by means not shown, at the respective rates of 180, 120 and 75 interruptions per minute, as indicated by the numbers directly below the corresponding sections on the track diagram. Steady alternating current is supplied to the rails of section 10T, that is, this current is not coded and consequently the cab signaling equipment is nonresponsive thereto, so that a red stop signal is received and in addition an automatic brake application is incurred, if the train enters section 10T, in order to insure against overrunning signal 2A when section 1T is occupied or switch 1A is being operated. Corresponding protection is provided for a train in any of the sections; thus when a train stands in section 14T, steady or noncoded current is supplied to the rails of section 16T so that a following train on entering that section receives a red signal and is stopped before it reaches section 14T. Further consideration of the coded track circuits is not needed for an understanding of my invention, and accordingly these are represented as ordinary track circuits. It is to be understood that each track relay TR as shown is normally energized and that it releases when the rails of its section are shunted by a train and also in the event of a failure of the track circuit supply.

The train describing system employed in connection with my invention as shown in Fig. 1A includes two similar train reporting devices TD1 and TD2 controllable by train carried marker coils and located respectively at the entrance to the approach zone and at the entrance to the interlocking plant, in the rear of signal 2A, together with a storage indicator of the multiple unit type controlled thereby, which comprises a plurality of cascade connected units adapted to store indications of the route, class or destination of the trains for display in the order of their passage through the approach zone.

This train describer system is of the type disclosed and claimed in a copending application for Letters Patent of the United States, Serial No. 233,616, filed on June 26,

1951, by Henry J. Groenendale, now United States Patent Number 2,670,434 granted February 23, 1954.

In addition to its use for automatic route control purposes, an important function of the train describer system is to selectively light one of a plurality of lamps AE, BE, etc., to visually indicate the route, class or destination of an approaching train or the approach of an unclassified train. These indications may be displayed in a control tower for the guidance of an operator in setting up routes manually and also on a passenger station platform for the information of the public. The lighting of lamp AE indicates that the approaching train is to take route 2-6; the lighting of lamp BE indicates it is for route 2-8; while the lighting of lamp NE indicates the approach of an unclassified train, that is to say, one for which the route is not specified and for which a route must be set up by manual control. In addition, the train describer system permits work trains or the like which are not equipped with marker coils to move into or out of the approach zone without interference with the displayed indication.

The relative length of the approach zone with reference to the length and spacing of trains is assumed to be such that there is room for only two trains in the approach zone at the same time, and accordingly the storage indicator as shown comprises only two storage units. The first of these governs the display of indications by the lamps AE, BE and NE and comprises a lockout relay L1 and a plurality of indication storage relays A1, B1 and N1 of which one is provided for each indication to be displayed.

The second storage unit comprises the similar relays L2, A2, B2 and N2, and provides means for temporarily storing the indication for a second train which enters the approach zone at a time when the first unit is displaying the indication for a preceding train.

Any suitable arrangement of storage relays may be used, but the storage indicator shown herein is of the type disclosed and claimed in Letters Patent of the United States No. 2,171,756, granted September 5, 1939, to Lloyd V. Lewis.

The train reporting devices TD1 and TD2 may be of any suitable type, but as shown herein these correspond, in principle, to what is disclosed and claimed in a copending application for Letters Patent of the United States, Serial No. 213,776, filed March 3, 1951, by Richard Treharne, which has issued as Patent Number 2,753,550, dated July 3, 1956.

Each train reporting device includes a plurality of primary windings continuously supplied with alternating current of a distinctive frequency f_1 , f_2 or f_3 , which identifies the indication to be displayed by the corresponding one of the lamps AE, BE and NE. Each primary winding has an associated secondary winding to which it is effectively coupled only when a train carried coil tuned to resonance at the corresponding frequency is interposed, or at least is brought into proximity with the corresponding pair of windings. Under this condition a detector relay AD, BD or ND is operated by energy supplied by the corresponding secondary winding.

It will be evident therefore that when a train or vehicle V which is equipped with a coil tuned to resonance at any one of the frequencies f_1 , f_2 or f_3 passes the reporting device TD1, the corresponding detector relay AD, BD or ND will be momentarily and selectively energized.

The train reporting device TD2 is similar to TD1 but has all of its secondary windings connected to the same detector relay CN, and this relay is operated nonselectively when a vehicle V which operated relay AD, BD or ND on passing device TD1 passes the second reporting device TD2.

When a vehicle V equipped with a marker coil passes the reporting device TD1, a distinctive indication is registered by relay AD, BD or ND and is stored by energizing the corresponding relay of the second unit until the first unit is available, and is then transferred to the cor-

responding relay of the first unit, which stores the indication until the train passes the second reporting device TD2, and the indication is then cancelled by the operation of detector relay CN.

5 The indication may also be cancelled by the operation of an emergency key CNB.

The train identification received by the train reporting device TD1 is stored in the following manner, provided the second storage unit is available with relays A2, B2 and N2 released, and relay L2 energized as shown.

10 The operated detector relay AD, BD or ND energizes, over contact b of relay L2, the corresponding one of the storage relays A2, B2 or N2 which relay is held energized over a stick circuit and its contact d assumes its upper position, releasing relay L2, and if relays A1, B1 and N1 of the first unit are released, energizing relay L1. The energized relay A2, B2 or N2 then energizes, over contact b of relay L1, the corresponding storage relay A1, B1 or N1 of the first unit which by closing its contact e lights the corresponding lamp AE, BE or NE, and completes a stick circuit which holds the relay energized until relay CN is operated by the corresponding train on passing device TD2 to cancel its indication.

15 The stick circuits for the storage relays A2, B2 and N2 of the second storage unit have two connections to terminal B of the local source of energy, one of which includes back contact d of relay L1, which is now open, and the other of which includes back contacts d of relays A1, B1 and N1. The latter connection is opened when one of these relays picks up to release the energized storage relay A2, B2 or N2, which in turn releases relay L1 and reenergizes relay L2. This renders the second unit available for the reception of an indication of a second train from the reporting device TD1 where it will be stored until the first storage unit is again rendered available.

20 Heretofore train describer systems as used commercially have been arranged to count train movements by the occupancy of certain track circuits to insure that at least one and only one indication will be stored or cancelled for each train passage. This arrangement presents the practical difficulty that close manual supervision is required to properly correlate the stored indications with the corresponding trains due to the occasional occupancy of the controlling track sections by unidentified or unclassified trains or when switching movements have to be provided for involving the repeated occupancy of the track section at one end only of the controlled territory, or in the event a second train enters a controlling track section before it is vacated by a first train. A further difficulty is presented where alternating current track circuits are used, as in the system herein disclosed, due to the possibility of the temporary release of a track relay used to count train movements, as the result of a fault or switching in the alternating current power network from which the track circuit derives its energization.

25 These difficulties are avoided in the train describer system shown because its operation is wholly independent of track circuit conditions. In consequence, the system is nonresponsive to irregular train movements or to the passage of extra trains unless this is desired, in which case the system is readily made responsive by the provision of suitably tuned coils on such trains, and the system is particularly well adapted to automatic operation because the usual provisions for correcting errors in the transmitted indications due to such irregular train movements are not needed.

30 The fact that the train describer system is independent of track circuit operation presents a difficulty when the system is applied to automatic route control which has already been referred to, and which is overcome, as already explained, by controlling the change-over relay APBS in such a manner that the automatic route control remains effective only as long as each approaching train registers a route indication and thereby operates relay

The interlocking control system shown in Figs. 1B to 1F, inclusive, is of the route type and corresponds generally to the system disclosed and claimed in Letters Patent of the United States, No. 2,301,297, granted November 10, 1942, to L. V. Lewis. In this system the routes are set up and their entering signals cleared by the operation of push buttons PB, shown in Fig. 1B, which designate the opposite ends of the routes.

The push button 2PB, shown in Fig. 1B, for the entrance end of the automatically controllable routes, is arranged in accordance with the requirements of my invention to include a rotatable contact *d* for conditioning the system for manual or automatic control, in addition to the usual push contacts *a* and *b* and pull contact *c*. In the manual control position the button 2PB controls the associated selecting relays by the operation of a repeating relay 2PBR over its contacts *a* and *d*, and its functions are similar to those of the others.

The circuits for the selecting relays of Fig. 1B are connected to terminal B of the local source of current at a front contact *b* of the track relay 1TR or 2TR for the track section at the entering end of the corresponding route, and to terminal N of the same source over wires 25 and 26 and back contacts of the switch control and indication relays of Fig. 1C as hereinafter traced in detail. For a general understanding of the mode of operation it will suffice to point out that when the system is in the condition shown the pressing of button 2PB operates relay 2PBR and thereby energizes the selecting relays ANE and RE for the diverging routes 2—6 and 2—8, button 4PB controls the selecting relay BNE for route 4—8, button 6PB controls the selecting relay ANW for route 6—2, and button 8PB controls the selecting relays RW and BNW for the diverging routes 8—2 and 8—4.

Each selecting relay, when operated, is held energized over a stick circuit including its own front contact *a*, the "pull" contact of the associated push button, and contact *b* of the track relay 1TR or 2TR for the track section at the entrance end of the route.

The operation of the selecting relay for either of two converging routes prevents the operation of the other by the opening of its back contact *e*, as shown for relays RE and BNE, and also for the similar relays RW and ANW. Each operated selecting relay also opens, at its back contact *b*, the pickup circuit for the selector relay for the opposing route, as shown for relays ANE and ANW, RE and RW, and BNE and BNW.

In addition, each operated selector relay, by closing its front contact *b* or *c*, conditions an exit stick relay XS for operation by the push button for the exit end of its route. Thus, relay 6XS is controllable by button 6PB when relay ANE is energized, and relay 8XS is controllable by button 8PB when either relay RE or BNE is energized. Likewise, relay 2XS is controllable by relay 2PBR when either relay ANW or RW is energized and relay 4XS is controllable by button 4PB when relay BNW is energized.

Under automatic operation, relay APBS is energized and its contacts *b* and *c* complete circuits by which a repeating relay AP or BP for the indication storage relay A1 or B1 of the train describer system is energized concurrently with the display of a route indication for route 2—6 or 2—8 by lighting lamp AE or BE. By closing its contacts *a* and *b* relay AP energizes relays ANE and 6XS, or relay BP energizes relays RE and 8XS, with the same effect as when these relays are energized by manual control.

The energization of an exit relay XS closes a circuit in Fig. 1C for a relay NLP or RLP, depending upon whether the switches are to be operated to normal or reverse for the selected route. These relays are identified as lever repeater relays because they may also be operated by moving a normally inactive emergency switch lever 1SW to its respective normal and reverse positions.

When relay NLP is energized, its back contact *e* in-

terrupts the circuits for relays RE and RW, and when relay RLP is energized, its back contact *e* interrupts the circuits for relays ANE, ANW, BNE and BNW. In this manner if two selecting relays ANE and RE or BNW and RW for diverging routes have been energized, the operation of relay NLP by the selected exit relay releases relay RE or RW, while if relay RLP is operated, it releases relay ANE or BNW.

Relays NWS and RWS are switch operating relays which govern the power operation of the track switches 1A and 1B to their respective normal and reverse positions in the conventional manner. These relays are controlled by relays NLP and RLP over front contacts *b* and *c* of a switch locking relay LS which is energized only when it is proper to operate the track switches, its circuits including front contacts *d* of the track relays 1TR and 2TR of Fig. 1A and of an approach locking relay AS, shown in Fig. 1F, for each signal which governs traffic movements over switch 1A or 1B.

10 The operation of relay NLP or RLP to be effective must be made at a time when relay LS is already energized, otherwise relay LS is prevented from picking up by the opening of back contact *b* of relay NLP or RLP.

When the track switches 1A and 1B complete their 15 operation in response to the operation of relay NWS or RWS a switch correspondence relay NWC or RWC becomes energized and picks up the associated indication relay NWK or RWK, and the latter completes a circuit in Fig. 1D, prepared by the operated exit relay XS, for a 20 route check relay RR which selects the entering signal for the route.

The operated route relay RR, by opening its back 25 contact *c* in Fig. 1F releases the approach locking relay AS for the entering signal and this relay in turn releases relay LS in Fig. 1C. Relays LS by closing its back contact *d* or *e* maintains the operated indication relay NWK or RWK energized. If relay NWK is energized, its contact *c* maintains the circuits for relays RE and RW open, while if relay RWK is energized, its contact *c* 30 maintains the circuits for relays ANE, ANW, BNE and BNW open. This prevents the selection of any route which conflicts with the one established, as long as the switch locking is effective. The opening of contact *c* of the approach locking relay AS for the entering signal in Fig. 1B prevents the reversal of the traffic direction over an established route.

In addition, relay LS closes a back contact *f* or *g* in 35 Fig. 1E to complete a circuit for the mechanism for the entering signal for the selected route (identified by the reference character G prefixed by the designation of the signal) and the operated mechanism G opens its contact *a* in the circuit for the associated locking relay AS to hold that relay released until the signal is restored to stop.

A route established in this manner may be cancelled 40 manually by momentarily pulling the button PB for the entrance end, to open its contact *c*. This releases successively the operated selecting and exit relays, relay NLP or RLP, the operated relay RR and the operated signal mechanism G.

The closing of back contact *a* of this mechanism G and of back contact *c* of the associated route relay RR completes a circuit for a time element relay 1TER or 2TER, over a back contact *a* of the associated approach locking relay AS and a front contact *g* of the track relay 1TR or 2TR. The time element relay first opens a quick acting checking contact *c* in the signal mechanism circuit and then after a predetermined time locking period closes its timing contact *a* or *b* in the circuit for the controlling relay AS causing that relay to pick up to energize relay LS, and to open the circuit for the time element relay, which then returns to its initial condition in which its checking contact *c* is closed. Relay LS releases relay NWK or RWK to enable a conflicting route to be established.

When the system is conditioned for manual control,

the approach locking relay is reenergized automatically as soon as a train accepts the signal and enters the first section of the route. In this case the operated selecting relay is released by the opening of contact *b* of the track relay 1TR or 2TR, and the selecting relay then releases the operated exit relay XS which in turn releases relay NLP or RLP and the operated route relay RR. The signal mechanism G is released concurrently by the opening of contact *c* of the track relay 1TR or 2TR, and the associated approach locking relay AS is picked up at once over a back contact *e* or *f* of the track relay. The opening of front contact *g* of the track relay prevents unnecessarily setting the time element relay into operation which otherwise would occur with each train passage.

Although the approach locking relay AS is picked up automatically as the result of the passage of a train while the switch section is occupied, the switch locking relay LS is held released by the open front contact *d* of the track relay 1TR or 2TR, and relay LS holds relay 1NWK or 1RWK energized, so that the switch locking remains effective until the train vacates the switch section.

In Fig. 1F each of the pickup circuits for an approach locking relay AS which includes a back contact *e* or *f* of a track relay includes in series therewith a front contact *a*, *b*, *c* or *d* of a quick release, slow pickup relay POSR which is normally energized by current from terminals BX and NX of the alternating current track circuit power supply.

The purpose of relay POSR is to insure against the premature energization of an approach locking relay AS during the time locking period imposed by relay 1TER or 2TER in the event the track relay is released as a result of the temporary interruption of the alternating current power supply. This arrangement is disclosed and claimed in Letters Patent of the United States No. 2,167,027, granted July 25, 1939, to C. H. Lay.

If the system is conditioned for automatic control, the approach locking relay for the entering signal is not reenergized automatically when a train enters the automatically controllable route 2-6 or 2-8, for the reason that the circuit for the approach locking relay 2AS for that signal which includes contact *e* of the track relay 1TR is held open at back contact *e* of the change-over relay APBS, and in this case, relay 2AS is reenergized by the operation of the time element relay 1TER, at the end of a predetermined time locking period which begins when the train vacates the route and the track relay 1TR becomes energized, in the case of route 2-6, or when relays 1TR and 2TR are both energized in the case of route 2-8.

Relays 4AS and 8AS are controlled in a similar manner over back contacts *f* and *g* of relay APBS, for the reason that these relays are associated with routes 4-8 and 8-4 which conflict with the automatically establishable routes and which may be set up by manual control when the system is conditioned for automatic operation.

As already mentioned, front contact *g* of the track relay is included in the circuit for the time element relay to prevent its unnecessary operation when the approach locking relay is picked up automatically over a back contact of the track relay. Under automatic operation these contacts serve a different purpose, which is to insure that the time element relay does not begin operation until the route is fully vacated, and for that reason an additional contact *h* of the track relay 2TR is required in the circuit for the time element relay 1TER.

The operation of the apparatus of my invention under different assumed conditions will now be described, assuming first that the operator sets up the system for automatic route control of an approaching train equipped with a marker coil tuned to frequency f_1 .

The operator rotates button 2PB to the right to close its contact *d* and then presses it to momentarily close its contacts *a* and *b*.

The change-over relay APBS picks up over the circuit, from terminal N at contact *d* of button 2PB in its right-

hand position, which includes the winding of relay APBS, contact *b* of button 2PB, wire 21, front contacts *a* of relays 2TR, 1TR and 2AR and extends to terminal B at front contact *b* of the track relay 14TR. When button 2PB is released, relay APBS is held energized over the stick circuit which extends to terminal N over the right-hand contact *d* of button 2PB, and to terminal B over its own front contact *a*, wire 22 and contact *b* of relay 14TR.

When the train passes the reporting device TD1, the train carried coil effectively couples the primary coil supplied with current of frequency f_1 to its secondary coil causing the detector relay AD to be momentarily energized.

The closing of contact *a* of relay AD energizes the directional stick relay 14SR over front contact *c* of the track relay 14TR. Relay 14SR is arranged to have an adequate release period, normally several seconds, by the provision of a condenser of large capacity in parallel with its winding. The reporting device TD1 is so placed with reference to the location of the vehicle carried marker coil at the time the track relay is shunted due to the passage of the first pair of wheels of the vehicle over the insulated joints between sections 16T and 14T, that the track relay 14TR will release while relay 14SR is still in its energized position and will complete a stick circuit for relay 14SR which includes its winding and front contact *a*, and back contact *c* of relay 14TR.

By closing its front contact *b*, relay 14SR maintains relay APBS energized during the time the train is traversing section 14T. It has already been explained that the block section provides an overlap to prevent two trains from occupying the same section, and it follows that relay 14TR will pick up to release relay 14SR before a following train can enter section 14T.

In the storage unit system, relay L2 is held energized over the stick circuit which includes its own front contact *a* and the back contacts *d* of the storage relays of the second storage unit, and when relay AD is operated, relay A2 is picked up over contacts *b* of relays L2 and AD. Relay A2 is held energized over a stick circuit including its own front contact *a*. It will be noted that the pickup and stick circuits for relay A2 have two connections to terminal B, one over back contact *d* of relay L1 and the other over back contacts *d*, in series, of relays A1, B1 and N1.

When relay A2 picks up it releases relay L2, and energizes relay L1 over the circuit from terminal N which includes the back contacts *c* of relays A1, B1 and N1, the winding of relay L1, front contact *d* of relay A2, back contacts *d* of relays B2 and N2, and terminal B.

When relay L1 picks up it establishes a stick circuit over its contact *a* and completes a pickup circuit for relay A1 which includes front contacts *b* of relays L1 and A2, and it also opens one branch of the holding circuit for relay A2. Relay A1 picks up and completes a stick circuit at its contact *a* so that it remains energized. Relay A1 also opens the other branch of the stick circuit for relay A2 so that relay A2 releases, with the result that relay L1 releases and relay L2 is reenergized.

When relay A1 is energized, lamp AE is lighted over its contact *e* to display the indication for route 2-6, and relay AP in Fig. 1B is energized over front contact *b* of relay APBS, wire 23, and contact *b* of relay A1.

When relay AP picks up, it energizes relay ANE over the circuit which extends to terminal B over front contact *b* of relay 1TR, front contact *a* of relay AP, back contact *b* of relay ANW, and to terminal N over back contact *e* of relay RW, wire 26, back contact *e* of relay RLP and back contact *c* of relay RWK.

Relay ANE picks up and energizes relay 6XS over the circuit which includes front contact *b* of relay AP and front contacts *c* of relays ANE and 6AS.

In Fig. 1C, relay NLP is energized over front contact *d* of relay 6XS and back contact *a* of relay RLP. Since the track switches 1A and 1B are already in the position

11

required for route 2—6, with relays NWS and NWC energized, relay NWK is energized at once over contact *d* of relay NLP and contact *a* of relay NWC.

In Fig. 1D, relay 2RR is energized by the closing of front contact *b* of relay NWK and front contact *c* of relay 6XS.

In Fig. 1F, the opening of back contact *c* of relay 2RR releases the approach locking relay 2AS, which by opening its contact *d* in Fig. 1C, releases relay LS.

In Fig. 1E, mechanism 2AG is now energized over the route circuit from terminal B over front contacts *b* of relays 6AS and NWC, back contact *f* of the switch locking relay LS, the quick acting check contact *c* of the time element relay 1TER, front contact *c* of the track relay 1TR, back contact *b* of relay 2AS, front contact *a* of relay 2RR, front contact *c* of relay NWC, the winding of the mechanism 2AG for signal 2A, back contact *c* of relay RWC and front contact *b* of relay 2RR to terminal N.

It is to be understood that the indication displayed by the signal changes from stop to proceed or caution, when its mechanism is energized, to authorize the train to enter the established route.

Before tracing the further movement of the train for which the route has been established, it will be assumed that a second train, equipped with a marker coil tuned to frequency f_2 , passes the reporting device TD1 before the first train passes the reporting device TD2.

When the second train passes the reporting device TD1, relay BD will be momentarily energized and will energize relays B2 and 14RS, and relay B2 will release relay L2, by operations similar to those already described, and relay 14SR will be effective to maintain relay APBS energized during the passage of the train through section 14T as in the preceding example.

Since relay A1 is energized, relay L1 is held released and the route indication for the second train is stored by relay B2 of the second unit.

The second reporting device TD2 may be located a short distance in the rear of signal 2A, and it will be assumed that the first train has advanced to a point where its marker coil has passed the device TD2 but that the train has not yet passed signal 2A to shunt the track relay 1TR.

When the marker coil on the first train passes the device TD2, relay CN is momentarily energized and releases relay A1, cancelling the indication displayed by lamp AE and releasing relay AP. By closing its back contacts *c* and *d*, relay A1 energizes relay L1 and maintains the stick circuit for relay B2 closed after relay L1 picks up, and relay L1 picks up and completes the pickup circuit for relay B1 which includes contacts *b* of relays B2 and L1 so that relay B1 becomes energized and releases relay B2 which in turn releases relay L1. Relay B1 lights lamp BE to display the indication for route 2—8 for the second train and also energizes relay BP over wire 24 and contact *c* of relay APBS.

In Fig. 1B, relays ANE and 6XS remain energized over their respective stick circuits and the established route is not interfered with by the release of relay AP or by the energization of relay BP. Relay RE does not operate on closing contact *a* of relay BP because the connection to terminal N for relay RE over wire 25 is open at contact *e* of relay NLP and also at contact *c* of relay NWK. Relay 8XS is not operated by relay BP because its circuit, which includes contact *b* of relay BP, back contact *c* of relay BNE and front contacts *c* of relays RE and 8AS, is open at contact *c* of relay RE.

It will be evident therefore that the change in the route indication is without any effect upon the established route and that signal 2RA will continue to display its indication.

When the first train accepts signal 2A and enters section 1T, the track relay 1TR releases and in turn, re-

12

leases relays ANE, 6XS, NLP and 2RR, and deenergizes mechanism 2AG to put signal 2A to stop.

When the first train vacates route 2—6, relay 1TR picks up and completes a circuit in Fig. 1F for the time element relay 1TER which may be traced from terminal B over back contact *c* of relay 2RR, back contacts *a* of mechanisms 2AG and 2BG and of relay 2AS, front contact *g* of relay 1TR, front contact *f* of relay NWC through relay 1TER to terminal N.

Relay 1TER becomes energized and opens its quick acting contact *c* in Fig. 1E, and after a predetermined time interval, closes its contacts *a* and *b* in Fig. 1F, the closing of contact *a* causing relay 2AS to become energized to complete its stick circuit and to release relay 1TER. Since relays NLP and RLP are released, relay 2AS energizes relay LS which in turn releases relay NWK.

When relay NWK releases, terminal N is again connected to the circuits for relays RE and RW, and if relay BP is energized, relays RE, 8XS and RLP will become successively energized and will find relay LS in its picked-up position; relay RWS will become energized, relays NWS and NWC will release, switches 1A and 1B will assume their reverse position, and relays RWC and RWK will become energized. Relay 2RR will

be energized over back contact *c* of relay 2XS, front contact *b* of relay RWK and front contact *c* of relay 3XS. This releases relay 2AS, which will release relay LS and complete the route circuit in Fig. 1E which extends from terminal B at front contact *b* of relay 8AS over

contacts *c* of relays 2TR and 2TER, contact *b* of relay RWC, contact *f* of relay LS, contacts *c* of relays 1TER and 1TR, back contact *b* of relay 2AS, contact *a* of relay 2RR, back contact *c* of relay NWC, the winding of mechanism 2BG, front contact *c* of relay RWC and contact *b* of relay 2RR to terminal N, thereby clearing signal 2B for route 2—8.

The locking of the track switches by the time locking means is effective to prevent their operation as long as there is a train in any route which conflicts with the one which is establishable automatically by the operation of relay AP or BP by the train describer system even though a track relay is imperfectly shunted during the passage of the train.

The establishment of route 2—8 automatically, as described above, is prevented during the passage of a train over route 2—6 because relay 2AS is held released by the opening of back contact *e* of relay APBS until contact *a* of relay 1TER closes at the end of a time locking period which begins when front contact *g* of relay 1TR closes.

Similarly, the establishment of route 2—6 automatically during the passage of a train over route 2—8 is prevented until the end of a time locking period which begins when the train vacates the last section 2T of the route and closes contact *h* of relay 2TR, which in this case is included in series with contact *g* of relay 1TR because contact *f* of relay NWC and contact *d* of relay APBS are both open.

When the system is conditioned for automatic operation, route 4—8 or 8—4 may be set up manually by operation of the push buttons 4PB and 8PB, provided route 2—8 has not been already established to open contact *c* of relay RWK in the circuit for the selecting relays BNE and BNW. The establishment of route 2—8, but not of route 2—6, is prevented during the passage of a train over route 4—8 or 8—4 because relay LS is held deenergized by the release of relay 4AS or 8AS, and the latter relay is held released by the opening of back contact

f or *g* of relay APBS until contact *a* or *b* of relay 2TER closes at the end of a time locking period which begins when front contact *g* of relay 2TR closes.

A back contact of relay APBS is not included in the circuit for relay 6AS because this relay is released only when route 6—2 is set up, and neither this route nor route

8-2 can be set up when the system is conditioned for automatic operation.

An important condition is to be considered is when two successive trains have the same route. In this case relay AP or BP is released when the first train passes the second reporting device TD2 and the same relay is then reenergized by the route indication for the second train. The route selecting relay ANE or RE is released by the track relay 1TR and is reenergized by this relay when the first train vacates section 1T, so that signal 2A or 2B for the same route will clear for the second train as soon as the first train passes out of the block, which may be assumed to include one or more sections in advance of the switch sections, the circuits for which are not shown. No time delay is imposed as when the route for the second train is different from that of the first train, the switch locking remaining in effect in this case.

It will next be assumed that the system is conditioned for automatic operation, with relay APBS energized, that route 2-6 or 2-8 has been set up and signal 2A or 2B cleared for an approaching train by the operation of relay AP or BP, and that a following train which is equipped with a marker coil tuned to frequency f3 enters the approach zone. On passing the reporting device TD1, relay ND will be operated to energize relay N2 which will store the indication until conditions permit its transfer to relay N1. The directional stick relay 14SR will not be operated and in consequence the change-over relay APBS will be released by the track relay 14TR, thereby releasing relay AP or BP. When the first train enters the route, relay 2AS is picked up by the release of the track relay 1TR and the switch locking is released as soon as the train vacates the route.

In the event the second train is not equipped with a marker coil and the train reporting device is not actuated, the approach of the train is detected by the release of the track relay 14TR and relay APBS is released with the same effect as in the preceding example.

In either case, the operator will place contact d in its left-hand position and manually set up the route for the second train.

Although I have herein shown and described only one embodiment of my invention, it is to be understood that various changes and modifications may be made therein within the scope of the appended claims without departing from the spirit and scope of my invention.

Having thus described my invention, what I claim is:

1. In an automatic route control system for railroads, a train describer system for supplying indications of the routes for approaching trains in the order of their approach, a manually controllable interlocking control system for establishing routes for said trains corresponding to the route indications supplied by said train describer system, a change-over relay which is released when said interlocking control system is conditioned for manual operation and which when energized conditions said interlocking control system to automatically establish traffic routes in accordance with the indications supplied by said train describer system, manually operable means for energizing said change-over relay, and track circuit controlled means for maintaining said change-over relay energized only so long as route indications for the approaching trains continue to be supplied by said train describer system.

2. In an automatic route control system for railroads, a train describer system for supplying indications of the routes for approaching trains in the order of their approach, a manually controllable interlocking control system for establishing routes for said trains corresponding to the route indications supplied by said train describer system, manual change-over means which in a first position conditions said interlocking control system for manual control and in a second position enables it to be conditioned for automatic control by said train describer system, a change-over relay having pickup and stick cir-

cuits including a contact closed by said manual change-over means in its second position, said pickup circuit including a normally open manually operable contact and contacts which when closed indicate that there is no train occupying the routes indicated by said train describer system, and means effective when said change-over relay is energized for conditioning said interlocking control system to automatically establish traffic routes in accordance with the indications supplied by said train describer system.

3. In an automatic route control system for a stretch of railway track including an interlocking plant and an adjoining approach zone, a train describer system for registering indications of the routes for trains entering said approach zone, a manually controllable interlocking control system for establishing routes for such trains through said interlocking plant, a change-over relay which is released when said interlocking system is conditioned for manual operation and which when energized conditions said interlocking control system to automatically establish traffic routes in accordance with the indications registered by said train describer system, manually operable means for energizing said change-over relay, track circuit means for indicating when an approaching train enters said approach zone, and means controlled by said track circuit means for releasing said change-over relay when a train enters said approach zone unless an indication for its route is registered by said train describer system.

4. In an automatic route control system for a stretch of railway track including an interlocking plant and an adjoining approach zone, a train describer system for registering indications of the routes for trains entering said approach zone, a manually controllable interlocking control system for establishing routes for such trains through said interlocking plant, a change-over relay which is released when said interlocking system is conditioned for manual operation and which when energized conditions said interlocking control system to automatically establish traffic routes in accordance with the indications registered by said train describer system, a track section at the entrance to said approach zone having a normally energized track relay, pickup and stick circuits for said change-over relay including a front contact of said track relay, said pickup circuit including a normally open manually operable contact, and means controlled by said train describer system for maintaining said change-over relay energized during the time said track relay contact is open due to the presence of a train in said approach zone, said means being effective only if the train describer system has registered an indication of the route for such train.

5. In an automatic route control system for a stretch of railway track including an interlocking plant and an adjoining approach zone, a train describer system for registering indications of the routes for trains entering said approach zone, a manually controllable interlocking control system for establishing routes for such trains through said interlocking plant, a change-over relay which is released when said interlocking system is conditioned for manual operation and which when energized conditions said interlocking control system to automatically establish traffic routes in accordance with the indications registered by said train describer system, a manually controllable pickup circuit for said change-over relay including contacts responsive to the presence of a train in said stretch which are closed to enable the relay to be energized only when there is no train in said approach zone or in any portion of a route controllable by said train describer system, a stick circuit effective to maintain said change-over relay energized during the passage of a train through said stretch, and manually controllable means for opening said stick circuit.

6. In an automatic route control system for railroads, a train describer system for registering indications of the

routes for approaching trains in the order of their approach, an interlocking control system of the type having push buttons for the ends of interlocked traffic routes by means of which such routes may be manually established, means comprising a rotatable contact associated with the push button for the entrance end of the routes indicated by said train describer system, said contact having a first position in which said push button is conditioned for the manual control of such routes and a second position in which the momentary operation of the push button associated therewith conditions the interlocking control system to automatically establish traffic routes in accordance with the indications supplied by said train describer system, and means for terminating the automatic control of said traffic routes upon the approach of a train if a route for such train is not registered by said train describer system.

7. In an automatic route control system for railroads, a train describer system controllable by train carried devices and operable independently of trackway conditions to automatically register a distinctive indication when a train passes a first reporting point and to automatically cancel such indication when the same train passes a second reporting point, certain of said indications designating routes to be taken by the corresponding train after passing the second reporting point, an interlocking control system having manually controllable means for establishing said designated routes, a change-over relay which is in a first position when said interlocking control system is conditioned for manual operation and when operated to a second position conditions said interlocking control system to automatically establish the routes designated by said train describer system, manually operable means for operating said change-over relay between said two positions, and means controlled by trackway conditions and effective when said change-over relay is in its second position and a train passes said first reporting point without registering an indication of its route to automatically operate said change-over relay to its first position.

8. In an automatic route control system for railroads, a train describer system having two train reporting devices at spaced points controllable by train carried marker devices and adapted to store route indications of successive trains in a series of wayside indicators, means controlled by the marker devices on at least two trains which successively pass the first reporting device for storing their route indications concurrently in said indicator, each train registering its route indication on passing the first reporting device and cancelling such indication on passing the second reporting device, an interlocking control system controllable by said route indications for establishing traffic routes for said trains which correspond to their route indications, a track circuit having a normally energized track relay for indicating the passage of each train irrespective of whether or not it registers a route indication, and means governed by said track relay acting in the event a train passes said first reporting point without registering an indication of its route for preventing the automatic establishment of a route for such train.

9. In combination with a railway track layout which includes interlocked track switches for establishing different traffic routes, having signals for controlling train movements over the routes, an interlocking control system for establishing said routes, manually operable means for selecting the routes to be established, a train describer system automatically controllable by marker devices on approaching trains for indicating the routes through said layout for such trains, means for automatically selecting certain routes to be established by said interlocking control system in accordance with the route indications supplied by said train describer system, change-over means for establishing said interlocking control system for manual operation in the event a train approaches without affecting said marker devices, switch locking means rendered effective when a route is established and the enter-

ing signal conditioned for clearing to prevent the establishment of any conflicting route, means effective when an established route which conflicts with an automatically establishable route is traversed by a train for maintaining the switch locking for the established route effective for a predetermined time interval after such route is vacated by the train, and means effective when a manually established route which does not conflict with any automatically establishable route is traversed by a train for rendering the switch locking for the established route ineffective as soon as the route is vacated by such train.

10. In combination with a railway track layout which includes interlocked track switches for establishing different traffic routes, having signals for controlling train movements over the routes, an interlocking control system for establishing said routes, manually operable means for selecting the routes to be established, a train describer system automatically controllable by marker devices on approaching trains for indicating the routes through said layout for such trains, change-over means which in a first condition renders said interlocking control system controllable by said manually operable means and which in a second condition renders said interlocking control system controllable to establish certain routes automatically in accordance with the indications supplied by said train describer system, said manually operable means remaining effective to establish routes which do not conflict with any automatically established route, switch locking means for each route which when effective prevents the operation of the switches in such route, means effective when said change-over means is in its first condition for rendering the switch locking for an established route effective from the time its entering signal is conditioned for clearing until it is vacated after the passage of a train over such route, and means effective when said change-over means is in its second condition for maintaining effective the switch locking for an established route from the time its entering signal is conditioned for clearing until the end of a time locking period which begins when the route is vacated after the passage of a train over such route.

11. In an interlocking control system for establishing traffic routes by the operation of interlocked track switches and for controlling signals for governing traffic movements over the routes established by the operation of said switches, manually operable means for operating said track switches and for governing the clearing of said signals, a train describer system adapted to supply route indications to indicate the routes to be taken by approaching trains, means for automatically operating said track switches to establish the routes indicated by said train describer system and for automatically clearing the entering signals for such routes when established, change-over means for establishing said interlocking control system for manual operation in the event a train approaches without affecting said describer system, switch locking means for each route which is effective to prevent the operation of the switches of its route from the time the entering signal therefor is cleared until the route is vacated after the passage of a train over such route, and means for maintaining the switch locking for any route which has been established and which conflicts with an automatically establishable route as long as the established route is occupied by a train and for an additional period of time which begins when the train vacates the established route.

12. In an interlocking control system for establishing traffic routes by the operation of interlocked track switches and for controlling signals for governing traffic movements over the routes established by the operation of said switches, manually operable means for operating said track switches and for governing the clearing of said signals, a train describer system adapted to supply route indications to indicate the routes to be taken by approaching trains, means for automatically operating said track switches to establish the routes indicated by said train de-

scriber system and for automatically clearing the entering signals for such routes when established, change-over means for establishing said interlocking control system for manual operation in the event a train approaches without affecting said describer system, switch locking means for each route which is effective to prevent the operation of the switches of its route from the time the entering signal therefor is cleared until the route is vacated after the passage of a train over such route, means effective when a signal is manually put to stop to prevent the release of the switch locking for the route governed thereby for a predetermined time locking period, and means for maintaining effective the switch locking for any established route which conflicts with an automatically established route as long as the established route is occupied by a train and also for a time locking period which begins when the train vacates said established route.

13. In combination with a railway track layout which includes interlocked track switches for establishing different traffic routes, having signals for controlling train movements over the routes, an interlocking control system having manually operable means for operating the track switches to establish said routes and for governing the clearing of the signals for such routes when established, a train describer system which indicates the routes through said track layout to be taken by certain approaching trains, manually operable change-over means effective when operated to enable said train describer system to automatically operate the track switches to establish the routes indicated thereby and to condition the signals therefor for clearing when such routes are established, switch locking means for each route effective to prevent the establishment of any conflicting route from the time the signal for such route is conditioned for clearing until the route is vacated after the passage of a train or for a time locking period in the event the route is not occupied and the signal for such route is manually put to stop, non-storage means effective to prevent the establishment of a route by the manually operable means therefor in the event such means is operated at a time when the switch locking for such route is effective, and means associated with the switch locking means for each route which conflicts with one which is automatically establishable by said train describer system for maintaining such switch locking means effective for a time locking period following the passage of a train over such conflicting route.

14. In an interlocking control system, an approach locking relay for preventing the operation of track switches in a traffic route governed by a railway signal, manual control means and automatic control means for establishing said traffic route and for clearing said signal, a normally closed stick circuit for said relay including its winding and front contact, a second contact which is closed only when the signal indicates stop, and a third contact opened by the signal control means to condition the signal for clearing, a track relay for the first section

of such route, a time element relay, a change-over relay which is released when the signal is conditioned for manual control and which when energized conditions the signal for automatic control, two pickup circuits for the approach locking relay which include said second and third contacts, one including back contacts of said change-over relay and track relay in series, the other including a contact closed by the time element relay following its energization for a time locking period, and a circuit for energizing said time element relay including said second and third contacts, a back contact of said approach locking relay, and a front contact of the track relay.

15. In an interlocking control system, an approach locking relay for preventing the operation of track switches in a traffic route governed by a railway signal, manual control means and automatic control means for establishing said traffic route and for clearing said signal, a normally closed stick circuit for said relay including its winding and front contact, a second contact which is closed only when the signal indicates stop, and a third contact opened by the signal control means to condition the signal for clearing, a track relay for each section of such route, a time element relay, a change-over relay which is released when the signal is conditioned for manual control and which when energized conditions the signal for automatic control, two pickup circuits for the approach locking relay which include said second and third contacts, one including back contacts of the change-over relay and of the track relay for the first section of the route in series, the other including a contact closed by the time element relay following its energization for a time locking period; and a circuit for energizing said time element relay which includes said second and third contacts and a back contact of said approach locking relay, said circuit including a front contact of the track relay for each section of the route when the change-over relay is energized, and a front contact of the track relay for the first section only of the route when the change-over relay is released.
